CLAIM

The ornamental design for a cellular phone, as shown.

DESCRIPTION

FIG. 1 is a perspective view of the ornamental design of the present invention with the cellular phone in the closed position;

FIG. 2 is a front elevational view of the ornamental design of the present invention;

FIG. 3 is a rear elevational view of the ornamental design of the present invention;

FIG. 4 is a left side elevational view of the ornamental design of the present invention;

FIG. 5 is a right side elevational view of the ornamental design of the present invention;

FIG. 6 is a top plan view of the ornamental design of the present invention; and

FIG. 7 is a bottom view of the ornamental design of the present invention.

FIG. 8 is a perspective view of the ornamental design of the present invention with the cellular phone in the open position; and

FIG. 9 is a view of the ornamental design of the present invention with the cellular phone in the open position and the screen portion pivoted substantially orthogonal to its position shown in FIG. 8.
